TREATMENT OF HYDROCARBON OILS

Richard F. Davis, Chicago, Ill., assignor to
Universal Oil Products Company, Chicago, Ill.,
a corporation of South Dakota

No Drawing, Application May 21, 1931,
Serial No. 539,140

12 Claims. (Cl. 196—24)

This invention relates to the treatment of hydrocarbon oils and refers more particularly to the treatment of the lighter portions of crude petroleums produced either by straight run distillation methods or by the cracking of heavier residues to produce lighter fractions.

In a more specific sense the invention contemplates the treatment of relatively low boiling petroleum fractions by reagents capable of removing sulphur therefrom, specific methods and agents being disclosed which offer distinct improvements and advantages over the methods at the present time employed in oil refining in that they are more specifically directed toward the elimination of types of sulphur compounds particularly resistant to the action of the more readily available treating reagents such as sulphuric acid, plumbate solutions, metals and their oxides and many other treating agents.

Many types of sulphur compounds have been identified in the fractions of crude petroleums, representatives of the following groups having been found in large amounts: mercaptans, sulphides, disulphides, thiophenes, thiophanes, compounds of the sulfoxyl type containing both sulphur and oxygen and heterocyclic bodies containing both sulphur and nitrogen.

In the ordinary methods of refining petroleum distillates with sulphuric acid of varying concentration, the total sulphur content is reduced incidental to the production of finished distillates freed sufficiently from highly unsaturated organic derivatives to render them stable to oxidizing influences and capable of holding their color and other desirable properties in storage. To reduce the sulphur content below a certain point requires excessive amounts of sulphuric acid or other reagents, the reason being that the sulphur is combined in ring compounds of the thiophene or thiophane type and these compounds are less reactive than other groups of compounds, for example, compounds of the mono-olefinic type or the partially saturated closed-ring hydrocarbons. The reduction of sulphur content to a negligible point without removal of desirable hydrocarbons has been the object of much study and experimentation and it is the object of the present invention to disclose a method of treatment whereby this may be accomplished.

In one specific embodiment the invention comprises treating petroleum distillates after easily removable sulphur compounds have been treated out with commoner reagents, with halogens and the hydrogenated derivatives of such organic nitrogen compounds as pyridine, pyrrole, etc.,

the ring sulphur compounds being split up by this reaction with the liberation of sulphur as hydrogen sulphide and the formation of high molecular weight nitrogen compounds of a mixed type.

The most typical of the hydrogenated compounds which may be employed in the desulphurizing reactions is piperidine or pentamethyleneimine, this substance being produced by the direct hydrogenation of pyridine by any convenient method such, for example, by reduction with sodium in alcohols or the direct hydrogenation in the presence of reduced metals such as nickel or other active hydrogenating catalysts. Piperidine has a boiling point of 222° F. and is readily soluble in water and alcohols and to a limited but sufficient extent in mineral oil distillates which it is desired to desulphurize.

As the reactions comprised within the present invention are characteristic of the pyridine homologous series, the case of piperidine is merely cited as being that of a type compound since the nitrogen bases employed after suitable hydrogenation may be any of those obtained from such sources as bone oil or coal tar, or from the weak acid extraction of portions of crude petroleums that are particularly rich in such nitrogen compounds, such as, for example, are obtained from certain California petroleums. In the last named case, nitrogen containing distillates may be extracted with, for example, weak sulphuric acid of 15 to 20% concentration, the nitrogen bases liberated by neutralization of the acid with alkalies such as caustic soda or lime and the mixture of nitrogen compounds liberated hydrogenated by any suitable means to render them of a constitution necessary for the desulphurizing reactions.

It has been found also that the reactions of decomposition of the thiophene nucleus are best brought about following the attachment of at least one atom of halogen to the ring and it has also been found that the desired desulphurizing reactions occur under the least severe conditions of temperature and pressure when iodine is the halogen atom. Heterocyclic ring compounds containing sulphur are more reactive with halogens than the corresponding cyclic compounds containing no sulphur in the ring. The addition of halogens to the ring sulphur compounds may be accelerated by the presence of minor amounts of suitable catalytic substances. In the case of chlorine, the presence of finely divided iron or aluminum or their chlorides has been found to speed up the halogenating reactions and in the case of bromine and iodine good results have been ob-

tained in the presence of minor amounts of mercuric oxide.

The reactions of thiophene with hydrogenated nitrogen bases of the pyridine type are typified by the following structural equation:

15 It will be evident from the consideration of the nature of the above reaction that it would be facilitated by the presence of excess of base or such alkalies as caustic soda, ammonia, etc., which would tend to absorb the halogen acid and hydrogen sulphide resulting from the reaction and such has been found to be the case. It will also be evident that the reaction is novel in regard to the

20 fact that the sulphur contained in the thiophene ring has been completely removed as hydrogen sulphide, and that therefore the reaction given above applied to the residual sulphur compounds in petroleum distillates will effect their substantially complete decomposition with the reduction of the sulphur content of the distillates to a negligible point.

25 The halogen necessary for further reactions may be regenerated from the halogen acid or the salt by any suitable means such as the electrolysis of the salt and it is convenient to recover the nitrogen base necessary to the main reaction by the heat treatment of the heavy polymerized nitrogen bodies which results in their decomposition into lighter fractions. The process may be therefore made completely regenerative and cyclic.

30 The reactions characteristic of the invention may be brought about in a variety of ways and in a variety of different types of equipment, some of which will be briefly described. A distillate from which it is desired to remove thiophene sulphur may be caused to circulate from the bottom cone of an agitator back into the top through distributing means, proper amounts of halogen being added as the oil is circulated and in the case of iodine or bromine, certain minimum amounts of mercuric oxide. Chlorine may be passed in as a gas in the presence of finely divided iron or aluminum or their anhydrous chlorides. The solid substances may be introduced into the circulating pump as concentrates, slurries or suspensions in small amounts of the oil undergoing treatment or they may be gradually added to the body of oil in the agitator and become mixed with the oil during circulation, the amounts being minor and causing no trouble in operation. After this preliminary halogenating treatment, any solid materials may be removed by settling and decantation of the liquid or the final traces may be removed by filtering through porous media such as sand filters, fuller's earth, porous plates, etc.

35 40 45 50 55 60 65 70 75 The following desulphurizing reactions with piperidine commonly require superatmospheric temperatures and may be conveniently brought about prior to the redistillation of the treated oil by introducing the reagent into the stream of oil entering a tubular heating element in which sufficient heat is being added to enable the subsequent vaporization of the oil with the separation of light fractions of motor fuel boiling point range, the high molecular weight nitrogen compounds being recovered as a residue from the refluxes in the fractionating tower and the traces of hydrogen sulphide in the overhead dis-

tillate being removed by a light alkali soda treatment.

Kerosene may be substantially completely desulphurized in a similar manner, it being at times unnecessary to redistill the treated oil as the hydrogen sulphide and halogen acid may be removed by relatively minor treatments with caustic soda or other alkalies and the nitrogen bases removed by comparatively light acid treatment.

80 85 90 95 100 The process of the invention is readily adaptable to the treatment of hydrocarbon oil vapors such as those coming from the fractionator of a cracking plant, and may be used as a step in conjunction with other treatments that may be conducted upon such vapors prior to their condensation. For example, such vapors may be subjected to preliminary treatments for desulphurizing and other refining effects such as treatments with solid metallic or adsorbent contact materials or miscellaneous chemical treating reagents such as acid, alkaline or salt solutions and then the process peculiar to the present invention utilized to substantially rid the vapors of thiophene or cyclic sulphur compounds, this step being followed by further treatments or washings to effect the removal of hydrogen sulphide and acid reaction products, and final rectification to produce a treated end-point gasoline.

105 110 115 120 125 130 135 140 145 As an example of the results obtainable by a treatment comprised within the scope of the invention, a cracked pressure distillate produced from a California residuum by cracking the same under superatmospheric temperature and pressure may be found to contain sulphur to the extent of 0.5%. Treatment with caustic soda may effect the removal of dissolved hydrogen sulphide and certain of the more reactive mercaptans so that the sulphur content is reduced to approximately 0.4%. Further treatment with 66° Bé. sulphuric acid in amounts equivalent to 7 lbs. per barrel of oil may still further reduce the sulphur content to 0.2%, reduction below this point by the use of larger amounts of acid being accompanied by undesirable losses of material.

To eliminate the 0.2% sulphur still remaining, the oil may be treated with a small amount of chlorine in the presence of ferric chloride, the amount used being approximately equivalent to the amount of sulphur present or $\frac{1}{2}$ pound of chlorine per barrel. This chlorination may be effected at ordinary temperatures by circulation from and to an ordinary agitator as already mentioned. To effect the final desulphurization the treated oil may be continuously fed to a tubular heating element and an amount of hydrogenated nitrogen bases of the piperidine type equivalent to approximately $\frac{1}{2}$ pound per barrel admitted to the suction side of the pump. There may be also added a small amount of ammonia or other alkali and the mixture of oil and treating reagents elevated to a suitable temperature during passage through the coil, this temperature, for example, being usually within the range of 400 to 600° F., 500° F. being many times sufficient to produce substantially complete desulphurization. The heated products may be discharged into a suitable tower and overhead fractions of gasoline boiling point range produced which upon light caustic treatment to neutralize traces of acidic and sulphur compounds may be found to contain as low as 0.01% sulphur.

The foregoing description has indicated that the invention comprises a process of the substantial desulphurization of petroleum distillates by new and novel means, but the particular ex-

ample cited is only one of many and as such is not to be construed in a limiting sense on the broad scope of the invention.	derivative of a heterocyclic nitrogen compound containing at least five members in the ring.
By the term "heterocyclic nitrogen compound" employed in the claims, I mean a ring compound containing nitrogen in the ring.	6. In the desulphurization of hydrocarbon oils, the method which comprises treating the oil with a halogen selected from the group consisting of chlorine, bromine and iodine, and a hydrogenated derivative of pyridine. 80
I claim as my invention:	7. In the desulphurization of hydrocarbon oils, the method which comprises treating the oil with a halogen selected from the group consisting of chlorine, bromine and iodine, and a hydrogenated derivative of pyrrole. 85
1. A method of treating hydrocarbon oil to remove heterocyclic sulphur compounds therefrom which comprises, mixing a halogen selected from the group consisting of chlorine, bromine and iodine with said oil in the presence of a catalyst, and subjecting the resulting mixture in company with a homologue of piperidine to a relatively elevated temperature.	8. In the desulphurization of hydrocarbon oils, the method which comprises treating the oil with a halogen selected from the group consisting of chlorine, bromine and iodine, and piperidine. 90
2. A method of treating hydrocarbon oil to remove sulphur compounds of the thiophene type therefrom which comprises, mixing a halogen selected from the group consisting of chlorine, bromine and iodine with said oil in the presence of a catalyst, and subjecting the resulting mixture in company with a compound selected from piperidine and its homologues to a relatively elevated temperature.	9. In the desulphurization of hydrocarbon oils, the method which comprises treating the oil with a halogen selected from the group consisting of chlorine, bromine and iodine, and then heating the oil in the presence of a hydrogenated derivative of a heterocyclic nitrogen compound containing at least five members in the ring. 95
25 3. Steps in a process of desulphurizing hydrocarbon oil which comprises, mixing a halogen selected from the group consisting of chlorine, bromine and iodine with said oil in the presence of a catalyst, passing said mixture in company with a heterocyclic organic nitrogen compound and alkali to a heating zone wherein the same is raised to a relatively elevated temperature, said compound being selected from the group consisting of piperidine and its homologues.	10. In the desulphurization of hydrocarbon oils, the method which comprises treating the oil with a halogen selected from the group consisting of chlorine, bromine and iodine, and then heating the oil in the presence of alkali and a hydrogenated derivative of a heterocyclic nitrogen compound containing at least five members in the ring. 100
35 4. In the desulphurization of hydrocarbon oils, the method of removing ring sulphur compounds which comprises treating the oil with a halogen selected from the group consisting of chlorine, bromine and iodine and an organic nitrogen base selected from the group consisting of piperidine and its homologues.	11. In the desulphurization of hydrocarbon oils, the method which comprises treating the oil with a halogen selected from the group consisting of chlorine, bromine and iodine, and thereafter heating the oil in the presence of a hydrogenated derivative of pyridine. 110
40 5. In the desulphurization of hydrocarbon oils, the method which comprises treating the oil with a halogen selected from the group consisting of chlorine, bromine and iodine, and a hydrogenated	12. In the desulphurization of hydrocarbon oils, the method which comprises treating the oil with a halogen selected from the group consisting of chlorine, bromine and iodine, and thereafter heating the oil in the presence of a hydrogenated derivative of pyrrole. 115
